UNITED STATES PATENT OFFICE.

JOSEPH H. ADAMS, OF BROOKLYN, NEW YORK, ASSIGNOR TO THE TEXAS COMPANY, OF HOUSTON, TEXAS, A CORPORATION OF TEXAS.

PROCESS FOR THE CONVERSION OF LIQUIDS, FLUIDS, AND OILS.

1,320,726.

Specification of Letters Patent.

Patented Nov. 4, 1919.

Application filed December 31, 1914. Serial No. 879,907.

To all whom it may concern:

Be it known that I, JOSEPH H. ADAMS, a citizen of the United States, residing at Brooklyn, in the county of Kings and State 5 of New York, have invented a new and useful Process for the Conversion of Liquids, Fluids, and Oils, and of which the following is a specification.

My invention relates broadly to the art of 10 converting oils and distillates of the plain hydro-carbon series, as well as those of the aromatic series, into more volatile products resembling light oils, gasolenes, benzin and naphthas which are characterized by lower 15 specific gravities and boiling points, with the object in view of meeting the great demand for internal combustion engine fuels, gasolenes, oils and spirits of the aromatic series and naphthas for manufacturing and other 20 industries; and to augment the gradually diminishing supply of the natural product.

It is also within the scope of this invention to treat the various crude petroleums and their products having asphalt or tar 25 bases in such a manner that the oils driven off in vapors and those drawn off in liquid form, when collected, will have greater volume and lower specific gravity than the product obtained from similar oils by any 30 of the known and commonly practised methods of fractional distillation.

The object of this invention is to formulate and carry out in a continuous manner a process for bringing about the conversion 35 and transformation of oil by means of externally applying a high degree of heat to a chamber, the whole or a part of which is composed of heat enduring material, and, while containing hydro-carbon or other oils, 40 heating the walls of the chamber to a temperature of sufficient intensity to locally "crack" and convert the said oil into oils and spirits essentially different from the original untreated oil.

This invention is based on the fact that 45 petroleum oils and distillates can be successfully "cracked" and broken into those of lower specific gravities and boiling points by means of properly applied intense heat 50 without unduly converting them into large quantities of fixed gases; and that these oils, when transformed by decomposition and synthetic reconstruction, form new chemical

compounds, or products of a more valuable nature than the original untreated oils as 55 set forth in my Patent 976,975, November 29, 1910, and pending applications 417,714, 530,852 and 618,011.

By my process, however, it becomes quite feasible to convert a high specific gravity oil 60 into those of lower specific gravities such as benzol, toluol, benzin, naphtha and gasolene, by subjecting the oil or mixtures of oils to the powerful influence of properly applied external incandescent heat and decomposing 65 temperature of not less than one thousand degrees, Fahrenheit (1000° F.), and from a visible cherry red in color to a full white heat, according to the character of the oil to be treated.

My object in general is to provide a new method and process for successfully breaking up the hydro-carbon oils such as the low naphthas, kerosenes and fuel oils into those of greater commercial value comprising the 75 lighter naphthas and gasolenes, benzols and toluols to augment the natural supply now obtained by known methods of crude oil separation.

Broadly stated, my improved process, 80 which is in contra-distinction from mere fractional distillation methods, consists in subjecting hydro-carbon oil to a form of decomposition and reconstruction under the influence of intense heat and self-generated 85 vapor pressure, whereby the product obtained, when condensed, collected and separated, will have greater commercial advantages than the original oil.

The nature of the process is such that its 90 full disclosure may be greatly facilitated by describing certain characteristic features of an apparatus designed to carry out the same, and attention is directed to the accompanying drawings forming a part of this specification in which Figure 1 is an elevation and sectional drawing of the collective apparatus, and for all purposes of description 95 this will afford a clear and well defined view.

Fig. 2 is a section at the top of a furnace, 100 which will serve to illustrate a common form of heater and the correlated parts of apparatus.

Fig. 3 shows more clearly a form of release valve and vapor or liquid collector. 105

Fig. 4 is a top plan of the crown which is

mounted over the furnace or heater, and Fig. 5 is a plan of the hot plate or medium which, when heated to the proper incandescence brings about the conversion, as more fully set forth in the following description:—

In the drawings like characters of reference denote corresponding parts throughout the several views of which in Fig. 1, A represents a suitable supply apparatus or 10 reservoir serving as a source for the oil to be treated.

This source of supply can be somewhat elevated with respect to the converter C, so that the gravity tendency of the oil may augment its flow into the converter under the influence of the contained weight of oil, or 15 the ease with which it may be withdrawn and forced into the converter C by means of pump 5.

20 The fluid oil may be supplied to the container A through pipe 1, while at the same time the displaced air can escape through pipe 2, or this pipe may be connected with an air compressor which will maintain a 25 sufficient pressure over the surface of the oil to force it through discharge valve 3, pipe 4 and through the regulating feed valve 6, to the pre-heater B, of which 7 represents a pipe coil through which the oil flows and 30 is heated before entering the cracking chamber 9, of converter C, through pipe 8.

For obvious reasons, it is best to pre-heat the oil before it is admitted to the converter C, so that the heat in that part of the apparatus may be conserved for the more important function of "cracking", splitting 35 the molecules of and rapidly vaporizing the converted oils; and therefore the heater B, is provided wherein the oil to be treated

40 may be brought to any desired temperature within the coils 7, by any economical means of heating.

This oil heater B, is placed in the piping system between the source of oil supply A, 45 and the converter C, in a manner conducive to the best methods of admitting oil to the cracking chamber of the converter C.

The drawing shows one of the many diverse forms which the converter C may assume, and such converter here shown comprises a chamber 9 of oil containing capacity 50 having a heat enduring bottom plate 10, located directly over a heating medium or furnace 11.

55 The chamber 9, is connected by a pipe or neck 12 directly with an inclosed expansion dome 13, intended to contain both liquid and vapor, and closed at the top by means of cap 14.

60 A gage glass 15 and thermometer 16 can be arranged on the vapor and liquid dome 13, for the inspection of oil quantities and temperatures, which are regulated by the flow of oil through supply pipe 4, and controller valves 6.

A gage glass 15' is arranged on column 40 also, in order to inspect the location of oil in that part of the system.

The furnace 11 is provided and located under the liquid containing parts of converter C, as a means of generating intense heat by known methods of gas, fuel oil, coal or electricity, and this furnace is supported on legs or piers, if necessary, so that in the use of gas or fuel oil, the piping system, 75 valves and controllers 17 can be the more readily operated.

A pyrometer element 16' is arranged to extend through the walls of the furnace in order that temperature may be determined, 80 which, in this process is a very important feature.

Inasmuch as the vapors rising into and filling the upper part of the expansion dome 13 may, at any time, be so rapidly evolved 85 as to exert undue pressure; I have placed a collecting tank 18 and pop valve 19, in relation with the upper part of dome 13, by means of the pipe 20; so that any sudden pressure above a given number of pounds 90 necessary to carry on the process under normal conditions, will cause the pop valve 19 to act rapidly and relieve the excessive pressure.

A feature of primary importance is the 95 means for externally applying heat of intense temperature to the heat enduring plate 10, for the purpose of bringing about a more or less complete conversion of oil.

Preferably this feature is operated by gas 100 or fuel oil and air or steam under pressure, and comprises one or more jets 17, through which elements of combustion are forced into an inclosed furnace or retort 11, composed of a shell or container 11' as shown 105 in Fig. 2, lined with firebrick 21' and asbestos or magnesia filling 58, which together are intended to retain the heat as long as possible, for the purpose of maintaining the plate 10 at the proper and uniform temperature. 110

In the shown form this furnace 11, with its intake pipes 17, and outlet or exhaust flue 21, passing through stack 51, is made up in circular form to properly heat the 115 round plate 10, located at its top in the form of a cap; and while the design of heater may be varied to conform to the different shapes and styles of converters, this form is well adapted for the economical 120 use of gas and liquid fuels supplied under pressure to generate the required intense heat; especially for working in the oil and gas regions where the fuel cost is low.

The intense externally applied heat affects 125 the oil contained within the cracking chamber 9 in such a manner as to very effectually convert the same and is thus adapted to assist in a step of primary importance to my process.

I may here state that when operating upon certain oils it is desirable to localize the application of heat so as to prevent the spread of the heat in a lower degree of intensity than is necessary to efficiently "crack" the oil, but of a sufficient intensity to cause evaporation of undue amounts of oil at a distance from the intensely heated walls of the cracking plate 10, without bringing about the desired conversion.

To this end in the embodiment of the apparatus shown in Fig. 1, I have provided a crown plate 22, to which the "cracking" plate 10 is made fast with bolts drawn 15 against a gasket at its outer edge, and spaced them so that only a thin layer of oil comes in close proximity to the intensely heated surface of the plate 10 which, as shown at Fig. 5, is provided with slotted 20 holes 52, having parallel edges radiating from the center of the plate, so that as expansion or contraction takes place in the plate, a means is provided to prevent upsetting the anchorage bolts or breaking the 25 cracking chamber crown 22.

A more comprehensive idea of this crown can be had by referring to the drawing, Fig. 4, where in three ports 37, and three oil supply pipes 8" are definitely located to facilitate operation. This drawing also shows the series of ribs 59 radiating from the center, and which lend strength to this part of the apparatus.

The sight tube 22' provides a means of 35 inspecting the incandescence of the cracking plate 10, or the molten metal 10' (Fig. 2) while the converter is in operation; and also affords a port through which pieces of metal or alloy can be placed in the chamber 40 9, preparatory to its being melted.

To protect the plate 10 from burning out, or the destruction of the oil over its surface and its complete transformation into fixed gases, with a consequent heavy and clogging deposit of carbon, I employ a metal or alloy having a melting point consistent with the required "cracking" temperature for the oil to be treated; which, when brought to the proper degree of heat, becomes a fluid 45 metal 10' (Fig. 2) flowing over the top surface of the plate 10, where it can be seen through inspection sight 22', and remaining so during the process of oil conversion while the furnace heat is maintained at the proper 50 degree of intensity.

In this manner the oil does not come in direct contact with the heated plate 10, but is affected by indirect heat absorbed through the molten metal, and which treats it as required, but without the undesirable accumulation of carbon which is destructive to the 55 heat enduring plate 10.

Alternately, and for the treatment of certain oils, the molten metal or alloy can be omitted from the apparatus, when in opera-

tion, so that the oil may come in direct contact with the intensely heated surface of plate 10; and the choice between these two methods of oil contact is largely a matter of judicious oil practice over which no set rules 70 can govern.

In order to prevent furious agitation within the chamber 9, and dome 13, while the process is in operation, perforated baffle plates 23, are located on the rod 24, and 75 made fast so that they occupy a position within the connecting neck or pipe 12, and are held in place by means of a nut and gland 25, at the top of dome 13, through which it passes.

Owing to the excessive quantity of heat employed in this process, and the consequent volatilization of unconverted oils under ordinary atmospheric conditions, I have, by a series of valves and collecting tanks, 85 provided a means of carrying on the conversion process under a pressure of several atmospheres, if necessary, by setting the pop valves to operate at certain pressures, as may be indicated by gages 35 and 36, both for 90 the release of vaporized oil from the top of dome 13 through pop valve 19 and chamber 18, and liquid oil from the bottom of said dome through pop valve 26 and collecting tank 27.

In this manner I am able to reduce the undesirable vaporization without conversion to a minimum, and as a consequence the evolved oils are, in a large proportion 95 "cracked" and otherwise converted in character.

In addition to the intense heat employed for the purpose of conversion, I also may use superheated steam forced into the body of oil through pipe 8' and a small jet at its 100 point of entry 8" into the chamber 9, and regulate the supply of steam in proportion to the amount of oxygen required to combine with a certain quantity of carbon contained in the oil, and thus freeing the result- 105 ant vapors, the product of conversion, from a portion of undesirable carbon.

In Fig. 3, a detailed drawing shows a form of liquid or vapor trap, wherein 27 is the container or expansion tank, provided with 110 a tightly fitting cover 27' held on with bolts and a gasket at its outer edge.

The pop valve 26 is arranged centrally on an elbow of pipe 43, and made fast to the container with flanges or lock nuts 43'.

The pop valve can be regulated for various pressures by means of the rod and cross head 26', which projects through the cap 27', and is properly sealed by a stuffing box or gland.

Oil or vapor escaping through the pop valve 26, and collected within the chamber 27, is then discharged through pipe and valve 45' to its destination.

By the proper means of propulsion, the 130

oil will be constantly flowing toward and into contact with the intensely heated lower surfaces of the cracking chamber 9, to take the place of that already vaporized from 5 above, or that drawn from below the surface line of oil maintained in the dome C, as indicated by the dotted line X.

Newly admitted oil will in turn be "cracked" and changed in the apparatus 10 into lighter and more volatile products, which will pass off in the form of vapors through the tank 18 and gooseneck 28, into the pipe coils 29 of condensing apparatus D; and having been condensed in the usual 15 manner the condensate is discharged into collecting tank E, through trap tank 30, valve 30' and pipe 31; or through pop valve 32 and tank 33, then conducted through pipe 34, according to the method to be employed 20 for operation with the apparatus under partial or complete compression.

During the operation of the process for oil conversion by this method, the raw non-converted oils will be relieved of a certain 25 portion of free carbon, of which they are in part composed, as well as some of the foreign substances which it is desirable to eliminate.

This, of course, alters their chemical character 30 and converts them from one or more of the hydro-carbon series into others of an essentially different character.

The carbon and other sediment remaining on the top surface of plate 10, or the molten 35 metal 10' above it, can be removed from time to time by cooling down the furnace, withdrawing the oil, and opening the ports 37 in the cap 22; which are more clearly shown in Figs. 2, and 4, and with a narrow 40 scraper or long slicing chisel, the refuse may be removed.

Inasmuch as the precise degree of temperature at which the plate 10, should be maintained in practice, will largely depend 45 upon, and be varied with particular conditions, it will be sufficient to state that the temperature of the plate will generally vary from a cherry red to a full white heat, according to the nature of the oil to be treated, 50 and that at no time in the process of conversion will the plate 10 be below a temperature of one thousand degrees Fahrenheit, (1000° F.).

When operating, it has been observed that 55 apparently only a certain part of the fluid vaporized comes in direct contact with the intensely heated surface of the "cracking" plate 10, for the reason that the intensity of heat evaporates a certain portion of the oil 60 at a lower temperature than is required for "cracking" the oil.

Accordingly, the vapors passing into the dome will be composed not only of the oil which has been transformed; but will also 65 contain a certain portion of the unchanged

original oil in the form of vapors which, when condensed and collected, must be separated by one of the processes of fractional distillation, if a more or less perfect segregation is required.

Since some of the vaporized original and unconverted oil may tend to condense in the tank 18, after leaving the pop valve 19, and before reaching the gooseneck 28; a pipe 38 is connected to the bottom of tank 75 18, and leads back through pipe 39, into the neck 12, of the converter C.

In a like manner if vapors containing heavy molecules or spray of unconverted oil, rise to the top of dome 13, and pass out 80 through pipe 20, and condense before passing through valve 19, the condensate is led down through column 40, and into neck pipe 12, through pipe 39.

In this manner the already condensed unconverted oil may be passed into the system again to mingle, and possibly become converted, with the new supply of oil continually flowing into the cracking chamber 9.

The above specifically described apparatus may, of course, be modified greatly and yet be well adapted to carry out one or more of the essential correlated steps of my process which, having now described a form of apparatus, is carried on in the following 95 manner:

When operating under atmospheric conditions, and without pressure in the systems, oil is admitted to container A through pipe 1, the displaced air in the container 100 passing out through pipe 2, until a sufficient amount of oil is stored for progressive work.

The system is then supplied with oil from the container through valve 3, and pipe 4, passing pump 5, which is cut out by closing 105 valve 4', thereby allowing the oil to pass through valve 5' and precision valves 6, into the coils 7 of pre-heater B.

The oil circulating through these coils, where it is heated, is then passed through 110 pipe 8, into cracking chamber 9, of the converter C, where it is brought into contact with intense heat maintained in plate 10.

The oil is held at a uniform level in dome 115 13, as indicated by the dotted line X, for the purpose of supplying weight to hold the body of oil down against cracking plate 10, or molten metal 10', and also to provide a medium for the partial arrest of up-flowing converted vapors, which are rapidly evolved 120 by the treatment of oil subjected to intensely high temperature.

As the vapors rise through pipe neck 12, to escape into the upper part of liquid and vapor dome 13, an intense agitation is carried on within this pipe 12, which would cause undue disturbance over the surface of the oil at line X; therefore perforated baffle plates 23, are made fast to rod 24, which is attached to the top 14, of the dome 13, 130

by means of a nut and gland 25 and the lower end screwed into cracking plate 10, where it is held securely in place.

As the oil rapidly becomes heated and volatilized, and would expand to unreasonable bounds if confined in the dome for any length of time, the overflow pipes 41, are provided to carry off the surplus unconverted oil which flows down through them 10 into collecting chamber 42 and out through pipe 43 and valve 44, to pipe 45, through which it is admitted to the bottom of pre-heater B, and flows out of the top through pipe 46, to the overflow tank 47, from which 15 it is withdrawn by pump 48, and delivered through pipe 49, to container A.

This returned oil may then be supplied again to the converter through the system just described.

20 A certain small portion of oil having been "cracked", converted and vaporized, rises to the top of dome 13 and passes out through pipe 20, pop valve 19, in container 18, which is opened and made a free passage to goose-neck pipe 28.

It then passes through condensing coils 29, immersed in water contained in tank D, and flows through trap tank 30, valve 30', and pipe 31, into collecting tank E, 30 from which the condensate may be drawn off through valve 50.

An important feature of pre-heater B, is the vent pipe 53, at the upper end of pipe 46, through which air and gases may pass 35 to avoid vacuum or pressure within the container B, and which would interrupt the proper flow of hot oil through that apparatus.

When operating under complete pressure 40 brought about by the expansion, vaporization and partial retention of oil and vapors in dome 13, due to the applied heat to plate 10, as in a steam boiler, valve 5' in pipe 4 is closed. Valve 44 in pipe 43 is 45 also closed, as well as valve 30' in pipe 31.

The pop valve 26 in container 27, is set to the proper release pressure, also pop valve 19 in container 18, and 32 in container 33.

50 The valve 56, at the end of coil 29, is open, while the valve 57, in pipe 38 is closed; thus effectually sealing the system against operation under atmospheric pressure.

55 Oil is then withdrawn from container A, through valves 3 and 4', by pump 5, which forces it through pipe 4 and valves 6, to the pre-heater coils 7, and pipe 8, into the cracking chamber 9.

60 A certain portion of unconverted oil overflows from the surface level X, in the dome 13, and is conducted through pipes 41 to chamber 42, thence through pipe 43, to pop valve 26, in container 27, where, by the 65 self generated vapor pressure maintained

over the surface of oil in the dome 13, the pop valve 26 in tank 27, is caused to release and allow a portion of the oil to flow through pipe 45, into the lower part of pre-heater B, and escape from the upper part 70 of said container through pipe 46, to the overflow tank 47.

The residue oil may then be returned to tank A, as heretofore described.

That certain portion of oil which, having 75 come in contact with the hot plate 10, or molten metal 10' lying above it, and becomes vaporized; rises through neck 12, and body of oil contained in the lower part of dome 13, and expanding into the upper part of 80 the said dome, is driven off through pipe 20, pop valve 19, and into the condensing coils 29, through pipe 28.

Pop valve 32, in container 33, is set at a pressure sufficient to check the rapid flow 85 of condensate from the coil, and is therefore an adjunct in maintaining vapor pressure within the entire system from pump 5, to the release valve 32. Distillate can also be accumulated under vapor pressure, in 90 trap tank 30, then released through valve 30' and pipe 31. The oil, having passed the last checking point, then flows by gravity into the collecting tank E.

If a partial pressure only, is required in 95 the system, the valve 56 and pop valve 32, also valve 30' in pipe 31 are opened, thus giving a free run of vapor and condensate, at atmospheric pressure only, from the container 18, to the collecting tank E, at the 100 foot of the pipe train.

Gases which may be present in the distillate, or fixed gases made in the process of conversion, can escape through valve 54 and pipe 55, leading out from container 33, or 105 through valve 54' leading out from trap tank 30.

As the condensate collected in tank E, is of a complex nature composed of converted and un-converted original oil, it may be 110 withdrawn and separated by any of the methods of fractional distillation and the remainder returned to container A, for re-treatment as before.

From the foregoing disclosures it is apparent that I have succeeded in formulating a process well suited to the several objects in view, and that as a result I have made it possible, within commercial limits, to convert inexpensive available oils into products 120 of greater value.

In view of these disclosures, it is obvious to those skilled in the art, that my process may be carried out with different fluids by varied steps, and accordingly I intend that 125 all matter contained in this description shall be taken as illustrative and not in a limited sense.

I desire it to be understood also, that the language adopted in the following claims 130

is intended to cover all of the generic and specific features of this invention, and all statements of the scope thereof which, as a matter of language, might be said to fall therebetween.

5 The apparatus described in the foregoing specification is not claimed herein, but forms the subject matter of a process for accomplishing the required results, and, having 10 now described my invention, what I claim as new, and desire to secure by Letters Patent is:—

15 1. The herein disclosed process of converting high boiling point hydrocarbons into lower boiling point products which consists in confining a body of oil under vapor pressure, maintaining a portion of said oil relatively separate and distinct, subjecting said 20 separate portion of said oil to a cracking and converting temperature, and introducing superheated steam into the portion of said oil where said cracking temperature is applied.

25 2. The herein disclosed process of converting high boiling point hydrocarbons into lower boiling point products which consists in confining a body of oil in an inclosed chamber, maintaining a portion of said oil relatively separate and distinct, subjecting 30 said separate portion of oil to a cracking and converting temperature, maintaining superatmospheric vapor pressure on said body of oil, and introducing superheated steam into said body of oil.

35 3. The herein disclosed process of converting high boiling point hydrocarbons into lower boiling point products which consists in confining a body of oil in an inclosed chamber, maintaining a portion of said oil 40 relatively separate and distinct, subjecting said separate portion of oil to a cracking and converting temperature, introducing superheated steam into said oil where said cracking temperature is applied, condensing 45 the converted vapor products generated and maintaining self-generated vapor pressure on said oil undergoing treatment and on said vapors while being condensed.

50 4. The herein disclosed process of converting high boiling point hydrocarbons into lower boiling point products which consists in confining a body of oil under vapor pressure, maintaining a portion of said oil relatively separate and distinct, subjecting said 55 separate portion of said oil to a cracking and converting temperature, continuously introducing oil and superheated steam into said body of oil at the point where said cracking temperature is applied and continuously 60 conducting away and condensing the vapors generated.

55 5. The herein disclosed process of converting high boiling point hydrocarbons into lower boiling point products which consists in confining a body of oil in an inclosed

chamber, maintaining a portion of said oil relatively separate and distinct, subjecting said separate portion of oil to a cracking and converting temperature, continuously introducing oil and superheated steam into 70 said body of oil at the point where said cracking temperature is applied, continuously conducting away and condensing the vapors generated and maintaining vapor pressure on said confined body of oil and 75 on said vapors undergoing condensation.

6. The herein disclosed process of converting high boiling point hydrocarbons into lower boiling point products which consists in confining a body of oil within inclosed 80 containers, subjecting a portion of said oil below the surface to a local cracking and converting temperature, continuously introducing oil into said body at the point where it is subjected to the local cracking temperature at a rate greater than that at which the oil is converted, withdrawing oil from the upper portion of said body at such a rate as to maintain a substantially constant 85 volume and level of oil and condensing the converted products.

7. The herein disclosed process of converting high boiling point hydrocarbons into lower boiling point products which consists in confining a body of oil, subjecting a portion of said oil below the surface to a local cracking and converting temperature in excess of their volatilizing points, continuously introducing oil into said body at the point where it is subjected to the local cracking 95 temperature at a rate greater than that at which the oil is converted, withdrawing oil from the upper portion of said body at such a rate as to maintain a substantially constant 100 volume and level of oil, condensing the converted products, and maintaining self generated vapor pressure on said body of oil and on said vapors during condensation.

8. The herein disclosed process of converting high boiling point hydrocarbons into lower boiling point products which consists in confining a body of oil, subjecting a portion of said oil below the surface to a local cracking and converting temperature, continuously introducing preheated oil and superheated steam into said body of oil below the surface, withdrawing oil from the upper portion of said body at such a rate as to maintain a substantially constant 110 volume and level of oil, condensing the vapors of converted oil in free communication with said body of oil and maintaining self generated vapor pressure on said oil during conversion and on said vapors during condensation.

9. The herein disclosed process of converting oils which consists in confining a body of oil of considerable volume, subjecting a limited portion of said oil at the lower 115

120

125

130

135

part of the body to a local cracking temperature, continuously supplying preheated oil and superheated steam to said limited portion subjected to said cracking temperature, drawing off oil from the upper portion of said body to maintain a substantially constant volume of oil and condensing the vapors of the converted oil.

10. The herein disclosed process of converting oils which consists in confining a body of oil of considerable volume, subjecting a limited portion of said oil at the lower part of the body to a local cracking temperature, continuously supplying preheated oil and superheated steam to said limited portion subjected to said cracking temperature, drawing off oil from the upper portion of said body to maintain a substantially constant volume of oil, drawing off the converted vapors under pressure from above said oil and condensing them under pressure.

11. The herein disclosed process consisting in subjecting high boiling point hydrocarbons to an externally applied heat of intense temperature while contained in a heat enduring chamber, maintaining a self generated vapor pressure only in the chamber and to and through the condenser in free communication with said chamber, introducing superheated steam under high pressure into the body of oil undergoing transformation, locally cracking and converting the same into low boiling products essentially different from the original untreated oil, separating out the lighter and retreating the heavier residues.

In testimony whereof I affix my signature in the presence of two witnesses.

JOSEPH H. ADAMS.
